SIGMUND J. PENTLER AND OTTO R. SHORT, OF WAUSAU, WISCONSIN.

SHOE STRUCTURE.

Application filed August 6, 1927. Serial No. 211,159.

This invention pertains to an improvement in shoe structures, and more particularly to an improved welt for that type of shoe of the general stitch-down class.

5 The invention has primarily for its object to provide an improved type of welt, whereby maximum lightness and strength is obtained without affecting the flexibility of the shoe so highly essential to the comfort of the 10 wearer.

A further object incidental to the foregoing, is to improve the finished appearance of the shoe by providing a relatively close edge or sole extension.

15 Another object is to provide a welt which will allow two rows of stitching to be employed with but one row showing on the welt, resulting in an exceptionally neat appearance and at the same time a very strong structure.

20 Another object is to provide a welt structure which will materially facilitate the repair of a shoe by permitting the welt to be retained in position on the upper after the 25 outsole is removed for replacement.

A still further object is to provide an improved structure of insole of minimum thickness, and which is highly flexible and allows for the desirable features of the Goodyear 30 welt and yet eliminates the necessity of a 35 filler.

With the above and other objects in view, which will appear as the description proceeds, the invention resides in the novel construction, combination and arrangement of 40 parts, substantially as hereinafter described and more particularly defined by the appended claims, it being understood that such changes in the precise embodiment of the 45 herein disclosed invention may be made as come within the scope of the claims.

In the accompanying drawings is illustrated one complete example of the physical embodiment of the present invention constructed according to the best mode so far devised for the practical application of the 50 principles thereof.

Figure 1 is a fragmentary perspective view of a shoe constructed in accordance with the 55 present invention, and partly in section to fully illustrate the structural details.

Figure 2 is a similar view of a modified form of the invention, and

Figure 3 is a fragmentary perspective view, partly in section, illustrating the man-

ner in which the insole is formed and the upper attached thereto.

Referring now more particularly to the accompanying drawings, the present invention, as illustrated, is applied to that general class 60 of shoe structures commonly termed "stitch-down," wherein the edge of the upper is turned outwardly and secured to the outsole by means of a welt strip positioned on the outturned edge of the upper and stitched 65 through to the outer sole. The numeral 1 designates the upper, and while the lining is omitted in the present illustration for the purpose of simplicity, it will be readily understood that the same would be employed in 70 most instances, its presence or omission in no way affecting the essential features of the invention.

Instead of the large single welt strip employed in conventional stitchdown shoes, it 75 is proposed to use a welt 2 formed from a comparatively thin strip of material, preferably leather, and folded upon itself to provide upper and lower flaps 3 and 4, respectively. By this construction it will be readily seen that a very thin strip of material may be employed, which, by folding upon itself, offers maximum strength and at the same 80 time great flexibility.

In order to facilitate repair of the shoe, 85 and particularly resoling, it is essential to secure the welt to the upper independently of the fastening means which secures the outsole. This is accomplished in the present instance by a line of stitching 5 which passes 90 through the fold of the welt strip 2, the upper 1, and the insole 6. Thus it will be seen that both the upper and the welt strip are securely attached to the insole, permitting removal of the outsole without affecting the welt, which 95 is highly desirable in repairing a shoe, as the operation of properly attaching the welt is a difficult one, and one which has always caused repair men considerable trouble in connection with conventional stitch-down types of shoes. 100

In addition to facilitating repair of the shoe, the stitching 5 also serves to retain the original shape of the shoe, as the upper is securely held in place against spreading.

In forming the insole 6 the edge is first cut 105 away to provide a comparatively thin extension 7 and a marginal shoulder 8 against which the upper and welt strip are held during the inseaming or attaching operation. Heretofore it has been common practice in 110

the manufacture of insoles to form a shoul-
dered extension of considerable thickness on
the marginal edge of the insole and then skive
or channel towards the shoulder, from the in-
side of the sole, to provide a channel opposite
the shoulder to allow the inseaming opera-
tion. By this method the inseaming passes
through what might be termed the in-be-
tween material—that is, the material between
the shoulder and the inner edge of the chan-
nel or groove, and not through the lip proper.
This requires an extremely thick insole in
order to provide sufficient material to hold
the stitching which secures the upper, and a
shoulder of sufficient depth against which to
hold the upper when inseaming.

As stated in the preceding objects, the
present invention aims to overcome objection-
able features of conventional insoles con-
structed in accordance with the foregoing de-
scription, by the provision of a sole of mini-
mum thickness and a comparatively thin lip
to which the upper is attached. This is ac-
complished by cutting away the marginal
edge a maximum depth to form the shoulder
8, and thereafter forming a comparatively
thin lip 9 by chanelling or cutting the sole
outwardly, it being particularly noted that
the channel formed by cutting the lip is con-
siderably below the plane of the shoulder 8,
as clearly shown in Figure 3.

The foregoing structure permits an exception-
ally thin insole to be used, and at the same
time allows a maximum marginal surface
against which to hold the upper during the
inseaming operation. This results in a very
light, flexible sole, and considerable saving
in material. Also, due to the fact that only
a very thin lip is required, the bottom of the
insole is exceptionally flat, thus eliminating
the necessity of a filler.

It will also be seen that the upper is in-
seamed to the flap 9 proper and not through
the material between the inner end of the
channel and the shoulder 8. In ordinary
structures this would not be practical as the
relatively thin lip provided in the present in-
stance would be insufficient to hold the upper.
However, in the present invention this struc-
ture is permissible, in that a second row of
stitching 10 is provided which passes through
the lower flap 4 of the welt strip 2, the out-
turned edge of the upper, and the outsole. In
addition to the stitching 10 for securing the
welt, upper, and outsole, a second row of
stitching 11 is employed which passes
through both flaps of the welt. Thus it will
be seen that the upper is held by two rows of
stitching independent of that which secures
it to the flap 9, thus relieving strain on the
flap and permitting the same to be of a mini-
mum thickness. In practice, a canvas lining
is cemented to the underside of the insole and
serves as a reinforcement for the lip 9, but
65 inasmuch as this forms no part of the pres-

ent invention, the same is omitted from the
drawing.

It will further be appreciated that by use
of the double flap welt two rows of stitching
may be employed for securing the welt, up-
per, and outsole, without detracting from
the appearance of the shoe by having two
rows of stitching visible on the welt strip,
which would result in a heavy, cumbersome
appearance. Further, in that the stitching
passing through the lower lip 4 may be posi-
tioned close to the fold of the welt, an ex-
tremely close edge may be had without de-
tracting from the strength of the shoe.

Also, in some instances, where a very light
shoe is desired, the upper flap 3 may be se-
cured by gluing or cementing, instead of
stitching, although in heavier types of shoes
where the maximum strength is desired, the
two rows of stitching through the welt, up-
per, and outsole, are employed.

The only distinction between the struc-
tures illustrated in the accompanying draw-
ing resides in the fact that the middle sole
12, illustrated in Figure 1, is eliminated in
the modification shown in Figure 2. Where
the middle sole is employed, the row of
stitching 10 passing through the lower flap
4 of the welt need not necessarily go through
the outsole, as one of the primary features of
this securing means is to cooperate with the
stitching 5 and 11 to securely hold the upper,
and this is accomplished equally as well by
merely stitching through the welt flap 4,
the upper, and the middle sole 12. Also, in
some instances, this may be desirable, as it
entirely eliminates any visibility of the
stitches 10, which gives the shoe a light and
neat appearance.

While the stitches have been referred to
throughout the preceding description, it is
to be understood that any suitable means of
attaching may be employed, such as staples,
or the like, without departing from the in-
vention.

From the foregoing it is obvious that an
exceptionally strong and flexible shoe has
been provided, which is neat in appearance,
easy to repair, and which will retain its orig-
inal shape for a long period.

We claim:—

1. A shoe structure comprising an upper
having an outturned edge, an insole, a welt
formed from a strip of relatively thin ma-
terial folded upon itself, securing means
passing through the fold of said welt, the
upper, and the insole, an outsole, securing
means passing through the lower flap only
of the welt, the outturned edge of the upper,
and the outsole, and a line of stitching pass-
ing through both flaps of the welt, outturned
edge of the upper, and the outsole.

2. A shoe construction comprising an up-
per having an outturned edge, an insole pro-
vided with a relatively thin marginal exten-

sion to form a shoulder around the entire edge of the tread portion and a relatively thin lip formed by channeling the insole adjacent its edge, a welt strip formed of a strip of material folded upon itself to form upper and lower flaps, a row of stitching passing through the fold of said welt strip, the upper, and the lip of said insole, a second sole adjacent the insole and engaged by the out-
5 turned edge of the upper, securing means passing through the lower flap only of the welt, the outturned edge of the upper and said second sole, and a line of stitching passing through the welt, the outturned edge of the upper and said second sole.
10 3. A shoe construction comprising an upper having an outturned edge, an insole provided with a relatively thin extension around the entire edge of the tread portion to form a marginal shoulder and a relatively thin lip
15 formed by channeling the insole adjacent its
20

edge, the inner end of said channel lying in a plane below that of the marginal shoulder, a folded welt disposed on the outturned edge of the upper, securing means passing through the fold of said welt, the upper, and the lip of said insole below the bottom of said channel, a second sole adjacent the insole and engaging the outturned edge of the upper, securing means passing through the lower flap only of the welt strip, the outturned edge of the upper and said second sole, and a line of stitching passing through both flaps of the welt strip, the outturned edge of the upper, and the second sole.
